UNITED STATES PATENT OFFICE.

NICKOLAS FINK, OF EDMORE, MICHIGAN.

COMBINED KING-BOLT AND CIRCLE FOR VEHICLES.

SPECIFICATION forming part of Letters Patent No. 299,367, dated May 27, 1884.

Application filed March 17, 1884. (No model.)

To all whom it may concern:

Be it known that I, NICKOLAS FINK, a citizen of the United States, and a resident of Edmore, Montcalm county, Michigan, have invented a Combined King-Bolt and Circle for Vehicles, of which the following is a specification.

The object of my invention is to construct in a simple and economical manner a combined king-bolt and circle or fifth-wheel for vehicles; and this object I attain as hereinafter set forth, reference being had to the accompanying drawings, in which—

Figure 1 is a perspective view of the device, the parts being detached from each other; Fig. 2, a front view, Fig. 3 an end view, and Fig. 4 a plan view, of part of the device.

A is a box which fits snugly to the axle x, and is secured thereto by clips a, or in any other suitable manner. This box has a tubular projection, b, for the reception of the king-bolt B, which can turn freely in the projection, but is confined vertically thereto by a nut, d, adapted to the threaded lower end of the bolt. The head F of the bolt is segmental, and bears upon a segmental projection, f, formed on the box A, and upon the beveled edge or periphery of the said segmental head F bears lugs g, which are beveled to conform to the said edge, and serve to guide the head and aid the nut d in preventing vertical movement of the bolt.

To a projection, G, on the head F is hung, by means of a pin, h, a bar, J, to which is secured, by clips i, the lower portion of the spring K, which supports the front end of the vehicle-body, the upper part of the spring being connected to said body in any suitable manner. The axle can turn freely on the king-bolt, the movement being steadied by the bearing of the segmental head F on the projection f, and by the guiding and retaining lugs g.

When it is desired to detach the axle, the nut d is removed and the axle turned so as to free the head F of the bolt from the control of the lugs, thus allowing the body of the vehicle to be raised until the king-bolt is clear of the box A.

The device described, while serving the purpose of the ordinary fifth-wheel, is more compact and economical than the same, and possesses greater strength.

I claim as my invention—

The combination of the box A, having a tubular projection, b, and bearing f, and the king-bolt B, having a segmental head, F, with the guiding and retaining lugs g, as set forth.

In testimony whereof I have signed my name to this specification in the presence of two subscribing witnesses.

NICKOLAS FINK.
